UNITED STATES PATENT OFFICE.

HENRY J. GAISMAN, OF NEW YORK, N. Y., ASSIGNOR TO AUTO STROP COMPANY, OF NEW YORK, N. Y., A CORPORATION OF NEW YORK.

DESIGN FOR A RAZOR-BLADE.

43,817.

Specification for Design.

Patented Apr. 8, 1913.

Application filed January 19, 1912. Serial No. 672,238. Term of patent 14 years.

To all whom it may concern:

Be it known that I, HENRY J. GAISMAN, a citizen of the United States, and resident of New York city, county of New York, State of New York, have invented a new, original, and ornamental Design for Razor-Blades, of which the following is a specification, reference being had to the accompanying drawing, forming part hereof.

The figure is a perspective view of a razor blade, showing my new design.

I claim:

The ornamental design for a razor blade, as shown.

HENRY J. GAISMAN.
